UNITED STATES PATENT OFFICE.

MICHAEL J. KEHOE, OF FORT WAYNE, INDIANA, ASSIGNOR OF ONE-THIRD TO BENJAMIN LEHMAN, OF FORT WAYNE, INDIANA.

ELECTRICAL SWITCH.

No. 866,590.

Specification of Letters Patent.

Patented Sept. 17, 1907.

Application filed November 2, 1905. Serial No. 285,516.

To all whom it may concern:

Be it known that I, MICHAEL J. KEHOE, a citizen of the United States of America, and a resident of Fort Wayne, in the county of Allen and State of Indiana, 5 have invented certain new and useful Improvements in Electrical Switches, of which the following is a specification.

This invention relates to improvements in electrical switches, especially for use in connection with the 10 transmission of high-tension electrical currents, and the objects thereof are, first: to provide apparatus for breaking, and closing, electrical circuits, and particularly those of the high-tension single or polyphase type; and second: to construct the apparatus so that both 15 the electrical and mechanical functions thereof will be performed without hindrance from climatic conditions, a further object being to afford means for opening overhead circuits at points unprotected from the weather.

The atmospheric variations and conditions to which 20 this invention is intended to be subjected in use are at times extremely violent, and it will be understood that the construction herein set forth has been especially devised to overcome difficulties due to opposing weather conditions.

25 The above objects are accomplished by the construction illustrated in the accompanying drawings, in which:

Figure 1. is a section of the apparatus on the line $x-x$ of Fig. 2; Fig. 2. is a transverse section of the same on 30 the line $y-y$ of Fig. 1; Fig. 3. is an end elevation of the apparatus; Fig. 4. is a detail view of one of the insulating supports for the contact terminals; Fig. 5. is a detail showing a sectional view of one of the bell-mouthed receivers; and Fig. 6. is a similar view of the flexible 35 end of one of the contact-terminals.

Similar numerals of reference indicate corresponding parts throughout the several views, and referring now to the same: 1—1 are vertical supporting posts, and 2—2 are horizontal beams secured to said posts. The 40 posts are arranged in opposite pairs, and the beams 2 are arranged thereon oppositely in parallel relation with each other. Cross arms 3 are rigidly secured upon the uppermost beams 2 and afford fixed support for the receiving contact terminals 4.

45 A movable frame 5 is pivotally supported at the upper ends of parallel swinging arms 6, the latter being arranged in opposite pairs and each of said arms has at its lower end a pivotal connection (as shown at 7) with the corresponding beam 2. The frame 5 has mounted 50 thereon a series of contact terminals 8 which are adapted to connect with the corresponding receiving terminals 4 when the frame is in closed position.

The connections of the receiving terminals with the cross-arms 3 and the connections of the contact-terminals 55 8 with the frame 5, are made with insulators 9 of

great efficiency. Each of said insulators has fixed upon its top an anchor-block 10 in which is fixed the corresponding terminals 4 or 8, thus the said terminals are held in rigid relation with the corresponding cross-arms, or frame, as the case may be.

Each of the terminals 4 has a receiving socket 11 and a bell shaped mouth 12 at one of its ends, and the adjacent end of the corresponding contact-terminal 8 has fixed thereon a flexible connecting plug 13 which is adapted to enter the socket 11 and form an electrical 65 connection with the corresponding receiving terminal 4.

The receiving-terminals 4 are connected with the corresponding ends 14 of the line-wires by means of suitable conductors 15, and the contact-terminals 8 have respective connections with the corresponding opposite 70 ends 16 of the line wires by means of flexible conductors 17. The ends 14 and 16 of the line wires are anchored respectively to insulators 19 which are mounted upon corresponding cross-arms 20, the latter being supported by the posts 1.

Baffle plates 21 are mounted upon the cross-arms 3 and range in vertical planes intervening between the respective pairs of contact-terminals.

In the operation of this invention, the frame 5 is 80 swung upon the arms 6 by applying mechanical force to said frame or arms so that the contact-terminals 8 will be carried forward and form connections with the corresponding receiving terminals 4, thus completing electrical connections between the opposite ends 14 and 16 of the corresponding line wires. While the apparatus is in this position electrical currents will be 85 conducted without obstruction from one end of each line wire to the corresponding opposite end thereof. When it is desired to break the electrical currents, the frame 5 is swung outward so as to carry the contact-terminals 8 from connection with the receiving terminals 4, thus opening each of the conducting circuits simultaneously. At the instant of separation between the respective terminals 8 and 4, electrical arcs will form and become extended until the distance between the 90 parting terminals become sufficiently great as will afford such resistance as to break the currents. The pivots 7 are so arranged in relative position to the frame 5 that when the latter is moved to open position it will be carried to a lower plane than when in its closed position, thus moving the contact terminals 8 oppositely to the upward tendency of the arcs and thereby affording further resistance to their maintenance than would be if the terminals were moved in a horizontal plane only, it being understood that the upward tendency 95 of the arcs is occasioned by attending heat.

Having described my invention what I claim as new, and desire to secure by Letters Patent, is:

1. In apparatus of the class described, supporting posts arranged in opposite pairs, each pair having horizontal 100

beams connected therewith; cross-arms fixed upon the uppermost beam of each pair of posts; receiving terminals fixed upon the cross-arms and electrically insulated therefrom; a movable frame; arms having pivotal relation with the horizontal beams, and having also at their upper ends pivotal connection with said movable frame and being adapted to maintain the latter in horizontal position; contact-terminals fixed upon the frame and electrically insulated therefrom, and each being adapted to connect with the corresponding receiving terminal; and corresponding line-wires having respective connections with the opposite receiving terminals and contact-terminals.

2. In apparatus of the class described, insulated receiving terminals mounted in fixed position; a movable frame; swinging arms pivotally mounted at their lower ends and having pivotal connections respectively with the movable frame to maintain the latter in horizontal position, and insulated contact terminals secured upon the frame, corresponding with said receiving terminals and arranged in alignment therewith, the frame being adapted to be swung to bring the contact terminals into and out of electrical connection with the corresponding receiving terminals.

3. In apparatus of the class described, a series of insulators in fixed position; a series of receiving terminals mounted upon said insulators; a movable frame; swinging arms having pivotal supports at their lower ends and having pivotal connections with the frame to support the latter in a horizontal plane; a series of insulators mounted upon the frame; and a series of contact-terminals fixed upon the latter insulators and corresponding with the receiving terminals and arranged in alignment therewith, the frame being adapted to be swung to bring the contact terminals into and out of electrical connection with the corresponding receiving terminals.

25

3. In apparatus of the class described, a series of insulators in fixed position; a series of receiving terminals mounted upon said insulators; a movable frame; swinging arms having pivotal supports at their lower ends and having pivotal connections with the frame to support the latter in a horizontal plane; a series of insulators mounted upon the frame; and a series of contact-terminals fixed upon the latter insulators and corresponding with the receiving terminals and arranged in alignment therewith, the frame being adapted to be swung to bring the contact terminals into and out of electrical connection with the corresponding receiving terminals.
